ELECTRON TUBE

Louis H. Crook, Washington, D. C.

Application June 30, 1942, Serial No. 449,104

12 Claims. (Cl. 250—27)

1
This invention relates to electron tubes having a plurality of electrodes.

It is an important object of this invention to provide an electrostatic shield for an electrode within an electron tube and to dispose the shield extending outwardly through the wall of the tube to shield a conductor connected to the electrode.

It is a further important object of this invention to provide integral shield means housing the current sources and the conductors connecting the current sources with the electrodes in an electron tube, and with the shield means extending through the wall of the tube to shield the electrodes of the tube.

It is a further important object of the invention to provide shielded sources of direct current shielded by shielding means extending through the wall of an electron tube, and to connect these direct current sources with other sources, or loads, external to the shielded sources by magnetic coupling.

It is an important object of this invention to assemble the electrodes, the direct current sources, and the conductors connecting the sources with the electrodes, of an electron tube within a shielding arrangement which enters through a wall of the tube to shield the several circuits of the tube against outside disturbing influences.

Other and further important objects of the invention will be apparent from the following description and the accompanying drawings.

In the drawings:

Figure 1 illustrates an electron tube having internal shields which extend through a wall of the tube to house external current sources and connecting wires. Part of the illustration is in section and part diagrammatic.

Figure 2 is an end view in plan of an electrode of the tube shown in Figure 1.

In Figure 1 there is shown an electronic tube or triode 10, which is provided with a cathode 11, a control grid 12, and an anode 13. The triode elements are housed in a glass envelope 14.

For purposes of illustration, the glass envelope is shown as substantially spherical, and the triode elements within the envelope generally define portions of spheres.

The cathode 11 is formed of an annulus 15, bent as shown in Figure 1, and a central terminal element 16 with a plurality of filaments 17 connected extending between the terminal 16 and the ring 15. Current is supplied to the cathode from a battery 18 through a conductor 19 connected to the terminal 16, and a return path

2
is provided by a somewhat hemispherical shield 20 connected to the ring 15 within the tube and extending outwardly from the tube as a conduit 21 and conductively connected to a casing 22 which contains the battery 18 and to which one pole of the battery is connected, as indicated at 23.

The cathode supply is, therefore, entirely contained in a shielded system. The metal of the shield is of good conductivity, so that the conductor 19 is effectively shielded against disturbing outside influences.

The control grid 12 may be a perforated plate or an annulus 24 supporting integrally connected grid wires as in conventional triodes, and the grid structure is bent to conform to the general shape of the cathode in spaced opposed relation to it. A generally hemispherical shield 25 is conductively connected to the ring 24 and this shield extends outwardly of the tube as a conduit 26 and envelopes the shield 20 in the tube and a portion of the conduit 21. The conduit 26 bends at an angle to the conduit 21 through an elbow, indicated at 27, and a wall of the elbow 25 is cut away to permit the conduit 21 to pass through it, and is insulated from the conduit 21 by insulation indicated at 28.

The conduit 26 is conductively connected to a casing 29 which houses a battery 30, and one pole of the battery is connected by a conductor 31 within the conduit 26 to a point on the conduit 21, as is indicated at 32. The other pole of the battery 30 is connected through a secondary winding 33 of a suitable transformer 34 to the wall of the casing. The primary winding 35 of the transformer 34 is outside the casing for connection to a suitable source indicated at 50, and the windings 33 and 34 are magnetically coupled by a core 36 of suitable magnetic material extending through a wall of the casing.

The grid circuit is, therefore, within an equipotential shielded system.

The anode 13 may be spherical and is suitably positioned with reference to the grid. The anode is also within an equipotential shielded system. A somewhat hemispherical shield 37 is placed within the tube and about the anode 13, and this shield extends outwardly of the tube as a conduit 38 which is conductively connected to a casing 39. The casing 39 houses a battery 40. One pole of this battery 40 is connected by a wire 41 within the conduit 38 to the anode 13, and the other pole of the battery is connected to the casing, as indicated at 42, through a primary winding 43 of a transformer 44. A sec-

ondary winding 45 is disposed outside the casing 39 for connection to a suitable load indicated at 51, and the windings 43 and 45 are magnetically coupled by a core 46 of suitable magnetic material. The anode and cathode casings are conductively connected to complete the cathode-anode circuit, and this conductive connection is indicated at 47.

The glass envelope 14 is suitably sealed to the metal conduits 26 and 38 by the conventional glass soldering method, and vacuum seals of suitable insulating material seal the space between the conduits 26 and 21, and the bore of the conduit 38, and the bore of the conduit 21, as indicated at 48, 49, and 53, respectively.

The leads 19, 31, and 41 are suitably supported in their housing conduits by thin and spaced insulating supports 52, if necessary.

The elements within the tube may be varied as to shape to suit specific uses of the tube.

According to the provisions of the patent statutes, I have set forth the principle and mode of operation of my invention and have illustrated and described what I now consider to represent its best embodiment. However, I desire to have it understood that within the scope of the appended claims the invention may be practiced otherwise than as specifically illustrated and described.

I claim as my invention:

1. An electronic tube including an envelope and an electrode within the envelope, a source of current connected to said electrode, and a conductive shielding conduit housing said source and entered in said envelope in conductive engagement with said electrode.

2. An electronic tube including an envelope and an electrode within said envelope, a source of current, a conductor connecting said electrode with said source, and conductive metallic shielding means connected to said source and engaging said electrode and housing said source and said conductor.

3. An electronic tube including an electrode, a source of current, a conductor connecting said source with said electrode, and conductive metallic shielding means connected to said source disposed enveloping said source and said conductor, said shielding means extending through the wall of the tube and being disposed in shielding relation about said electrode within the tube.

4. An electronic tube including an envelope and an electrode within the envelope, an external source of current, a first conductor connecting said source with said electrode, and a second conductor connecting said electrode with said source and enveloping said source and said first conductor both within and without said envelope.

5. An electronic tube including an electrode, a source of current outside said tube, conductive shield means housing said source and entered in said tube, and conductor means connecting said electrode and one pole of said source and disposed within said shielding means, said shielding means being connected to the other pole of said source and also to said electrode within the tube.

6. A non-grounded circuit arrangement including an electronic tube having an envelope, an electrode in said envelope, a source of energy connected to said electrode, and a conductive shielding conduit housing said source of energy and its connection to said electrode, said shielding conduit extending through said envelope and being shaped interiorly of said envelope to effect

a shielding of said electrode therein except for a predetermined path for electron flow, whereby the complete electrode circuit is shielded both inside and outside said envelope other than for said electron path.

7. In a non-grounded electronic tube circuit arrangement, an electronic tube including an envelope, a plurality of electrodes spaced from each other within said envelope, means connecting each of said electrodes with electrical apparatus outside said envelope, said means including conductive shielding conduits enclosing said outside apparatus and extending within said envelope to fully shield said electrodes and their associated circuits both inside and outside said envelope except for a predetermined path of electron flow within said envelope.

8. In an electronic tube, an envelope, a plurality of electrode circuits including inner and outer conductors and contained within the outer conductor extending into said envelope, shielding means inside said envelope shielding said electrodes one from the other except for a predetermined path of electron flow, and energizing means contained within said outer conductor outside said envelope.

9. In an electronic tube including an envelope, a cathode and an anode in said envelope, means connecting said cathode with a potential establishing apparatus outside said envelope, means connecting said anode in a potential circuit including apparatus outside said envelope, conductive shielding means enclosing the cathode potential circuit and extending within said envelope, conductive shielding means enclosing said anode potential circuit and extending within said envelope, and conductive means connecting together the shielding means for both said circuits outside said envelope.

10. A non-grounded circuit arrangement including an electronic tube having an envelope, a plurality of electrodes in said envelope, a source of energy connected with each said electrode, and conductive shielding means housing each said source of energy and shielding and forming a part of the respective electrode circuit independently of the other electrode circuits except for a predetermined path for electron flow within the envelope.

11. A non-grounded circuit arrangement including an electronic tube having an envelope, a plurality of electrodes in said envelope, a source of energy connected with each said electrode, and conductive shielding means housing each said source of energy and shielding and forming a part of the respective electrode circuit independently of the other electrode circuits except for a predetermined path for electron flow within the envelope, certain of said conductive shielding means being in the form of conduits, the inside surface of one of said conduits being used as one leg of one circuit and a part of the outside surface of the same conduit being used as a leg of another circuit.

12. An electronic tube comprising a glass envelope into which an electrode circuit extends, said circuit including a first electrode having a metallic casing extending without the envelope, another electrode circuit extending into said envelope, said other circuit including a second electrode having a metallic casing extending without said envelope and within the first said metallic casing, and energizing means for said circuits

within one of said metallic casings outside said envelope.
